BENJAMIN H. FLYNN, OF NEWKIRK, OKLAHOMA.

TURNTABLE EQUIPMENT FOR PAVING AND ANALOGOUS MACHINES.

Application filed July 8, 1926. Serial No. 121,203.

Well known types of mobile machines for paving with concrete, and certain types of cement mixers are provided with a skip for elevating a batch of the materials to be mixed and discharging such batch into a mixing drum. This skip, on the larger machines, is designed to permit dumping of a truck load of material into it at one operation and in order to so dump a truck, it is necessary that it shall be turned around and backed to the skip. To accomplish this, a turntable is usually provided to be rotated by hand after a truck has been driven forwardly onto it. This is necessarily a slow and arduous operation, requiring several laborers. Moreover, this turning is dangerous to those performing the operation, with the result that casualties are frequent.

Another drawback with the usual turntable is the difficulty experienced in moving it from one place to another, two or more teams or a tractor being commonly employed for this purpose. When paving, to obviate the necessity of moving the table any more than is absolutely necessary, it is usually placed on the grade quite a distance in advance of the paving machine, and after each truck is turned around by means of the table, it is backed to the skip and dumped. Very often, the truck cannot be gotten into proper position for dumping the entire load into the skip and expensive loss of time and trouble ensue.

It is to overcome such difficulties as those set forth, that I have provided the present invention, and with this end in view, said invention has been so devised as to embody novel structural features and unique relations of parts, hereinafter described and claimed, the description being supplemented by the accompanying drawings.

Figure 1 is a perspective view of the turntable equipment operatively connected with a well known type of paving machine, the skip of the latter being shown in its raised, discharge position.

Figure 2 is a perspective view illustrating the skip in lowered position, and in the present disclosure of the invention, it is this lowering of the skip which turns the turntable one-half revolution to reverse the truck previously driven onto it, permitting said truck to dump into the skip and then drive forwardly from the table.

Figure 3 is a perspective view with the

rotatable portion of the turntable removed, illustrating the manner in which elevation of the skip is utilized to raise the base of the turntable from the ground and place its weight upon carrying wheels, when said turntable is to be moved from one position to another, with the paving machine.

Figure 4 is a fragmentary top plan view.

Figure 5 is a top plan view of the central portion of the turntable base and associated parts.

Figure 6 is a vertical longitudinal section on line 6—6 of Fig. 5.

Figure 7 is a horizontal section on line 7—7 of Fig. 6.

Figure 8 is a detail transverse section as indicated by line 8—8 of Fig. 4.

Figure 9 is a horizontal section partly in elevation showing the preferred connecting means between the turntable equipment and the paving machine.

In the drawings above briefly described, 10 designates a portion of a well known type of concrete paving machine, said machine having a pivoted skip 11 at its front end 80 which is movable from a lowered, receiving position (Fig. 2) to a raised, discharge position (Fig. 1), said skip when in the latter position discharging its contents into the usual drum 12 of the machine 10. The skip is provided with the usual raising means, embodying two reaches of cable 13 passing over appropriate guides 14 and having suitable connection with said skip. These cables are wound upon the usual drum means (not shown) to elevate the skip, and when said cables are allowed to pay out, the skip lowers by gravity. In the preferred form of my invention, I make use of the weight of the skip, as it lowers, to effect turning of the turntable one-half revolution, so as to reverse a loaded truck on said table, and it will be observed that by so utilizing the weight of the skip to reverse the position of the truck, no added strain is placed upon any parts of the paving machine 10.

The paving machine is successively advanced along the grade, between the usual forms 15, said machine being ordinarily provided with endless treads 16 which travel 105 upon said grade. The turntable equipment which I have devised for use in connection with this or a similar machine, is disposed in advance of such machine and is connected with it, so that the two progress as a single 110

mechanism and always maintain proper operative relation. This turntable equipment will now be described.

A base B is provided with normally idle rollers or wheels 17 which may either run upon the forms 15 or upon the grade and may be shaped accordingly. Normally, this base B rests upon the ground, but provision is made, hereinafter described, for lifting 10 said base free of the ground and supporting its weight upon the wheels 17, when the turntable is to be advanced with the machine 10.

The rotatable portion R of the turntable is 15 supported by the base B and while it might be of flat-topped construction, it is preferably of frame-like form and embodies two channel-shaped tracks 18 to receive the wheels of a motor truck T. The base B 20 includes two channel-shaped approaches 19 which incline to the tracks 18, permitting a truck T to be driven forwardly onto said tracks as will be clear from Fig. 1. According to the present disclosure of the invention, 25 the truck is driven onto these tracks, when the skip 11 is raised, and provision is made for automatically turning the table portion R one-half revolution as said skip is lowered to receive the material from the 30 loaded truck. When the truck is thus turned around, its rear wheels are positioned so that they may travel rearwardly onto fixed elevated tracks 20 which are rigidly carried by the base B, and the front end of the skip is 35 provided with an elevated platform 21 or other desired means, onto which the rear wheels of the truck may be backed, to the limit permitted by the stop 22. Thus, the truck may be cleanly dumped into the skip 40 11, and the load will be discharged closer to the skip pivot 11', than is ordinarily possible. Hence, the machine may elevate the loaded 45 skip with the expenditure of less power than is now commonly necessary. Moreover, less strain is placed upon the cables 13 and associated parts.

After the truck has dumped its load into the skip 11, it may be driven forwardly off of the members 21, 20, as will be clear from 50 Fig. 2. Then, the skip 11 may be elevated to discharge its load and provision is made whereby this elevation of the skip will not move the turntable portion R. Thus, no 55 added load is placed upon the machine 10. After one truck leaves, the entire assembly of parts is in readiness to receive another truck, and the operations above defined, are then 60 repeated.

When the paving machine 10 is to be advanced along the grade, the wheels 17 are 65 brought into play to carry the weight of the turntable equipment and it may here be explained that when the base B and the portion R are elevated and their weight placed upon said wheels 17, the approaches 19 and the

tracks 20 are elevated bodily with said base to be advanced therewith. When the machine has been forwardly moved to the required extent, the weight of the turntable equipment is again taken off of the wheels 70 17 and permitted to rest solidly upon the grade.

A general understanding of the invention has been briefly given in the foregoing and it will be clear that the improved mechanism 75 may be constructed in detail, in a great number of ways, without departing from the spirit of or sacrificing any of the advantages of the invention. For illustrative purposes, one practical way of constructing the 80 machine, has been illustrated in the drawings and will now be specifically described.

The base B includes two parallel longitudinal sills 23 whose front ends carry the approaches 19 and whose rear ends carry the 85 tracks 20. These sills are rigidly secured to front and rear, transverse beams 24 which may be formed of channel steel, and near the outer ends of these beams, the latter are connected by inner and outer longitudinal bars 90 or beams 25 and 26 respectively. A third transverse beam 27 is preferably interposed between the beams 24 and secured to the members 23, 25 and 26. For a purpose to appear, the ends of the beam 27 are provided with cable guides 28, one pair of guides being disposed at each end of said beam.

The wheels 17 are carried by cranked axles 29 mounted in appropriate bearings at the ends of the beams 24, said axles having 100 upstanding arms 30, to which cables 31 are connected, said cables extending around the guides 28 and inwardly toward the center of the base, the inner ends of said cables being connected to two cable reaches 32. 105 which may, at the control of the operator, be wound upon a drum 33 (see more particularly Figs. 6 and 7). By so winding the cable reaches 32, the arms 30 move the cranked axles 29 in a manner to cause the base B to rise free of the ground, placing its weight upon the wheels 17. Provision yet to be described is made for driving the drum 33 or for permitting retrograde rotation of 110 said drum, the latter being allowed when the machine has been advanced to the required extent and is to be again lowered onto the ground.

The drum 33 is centrally disposed over the beam 27 and is suitably secured to a vertical shaft 34. The lower end of this shaft is mounted in a step bearing 36 secured to the beam 27, and the intermediate portion of said shaft passes through an opening in a bolster 37, the ends of this bolster being secured to the beams 23. The projecting upper end of the shaft 34, forms a central pivot for the rotary portion R of the turntable, but no weight of the table is carried by this shaft. Instead, the end portions of the tracks 130

are provided with radially positioned rollers 38 mounted in appropriate brackets 39, said rollers traveling upon an annular track 40 which is suitably secured to the base B. In 5 addition to the tracks 18, the table portion R preferably includes three transverse bars 41, 42 and 42', the ends of these bars being secured to said tracks. The bar 41 is centrally positioned and is formed with an 10 opening through which the shaft 34 passes. Thus, this shaft and associated parts constitute a central pivot about which the turntable portion R rotates, so that the rollers 38 need not be provided with flanges to 15 engage the track 40 and hence a great deal of friction is eliminated.

A large driving gear 43 is provided for the turntable portion R, said gear being secured to said table portion in any desired 20 manner. In the present showing, it is fastened by bolts or the like 44 to the transverse bar 41, and ball bearings 45 may if desired, be interposed between said gear and the bolster 37, it being of course understood that 25 similar anti-friction bearings could be used at any other desired points on the machine.

A short longitudinal bar 46 centrally disposed, is shown extending rearwardly from the beam 27 to the rearmost of the 30 beams 24. In any desired manner, this bar 46 supports an upstanding stub shaft 47 which is disposed behind and parallel with the shaft 34. Rotatably mounted on the upper portion of this stub shaft 47, directly 35 under an appropriate brace 48 for said shaft, is a driving pinion 49 which meshes with the gear 43. A drum 50 is rotatably mounted on the shaft 47, under the pinion 49 and a one-way driving connection, such as a ratchet 40 mechanism 51, is employed between said drum and pinion. This ratchet connection comes into play to drive the pinion 49 by means of the drum 50, so as to rotate the portion R of the turntable, when said drum 45 is driven in one direction. The ratchet connection also permits retrograde rotation of the drum 50, without similarly rotating the pinion 49.

A cable reach 52 is wound in such a direction upon the drum 50, that a pull upon said cable will drive said drum in table-turning direction. This cable reach 52, in the present disclosure, passes around a suitable cable guide 53 on the base B, around 55 other guides 54 and 55 carried by the machine 10, and is connected with the skip 11, there being some slack in said cable reach 52, when the skip is raised as in Fig. 1. Thus, by the time the skip has lowered to 60 such an extent as to well offset its weight from direct downward action on the pivot 11', this slack is taken up, and the weight of the skip in descending, then pulls upon the cable reach 52, effecting rotation of the 65 drum 50 in table-turning direction so as to

effect one-half revolution of the table portion R, reversing the position of the truck previously driven onto the tracks 18.

Any desired means, such as a brake 56, acting on a portion of the drum 50, may be 70 provided to arrest the movement of the rotatable table portion R, and a lever 57 has been shown suitably mounted upon the base B and connected by a cable or the like 58 with said brake 56, for the purpose of operating the latter.

Provision is made for rewinding the cable reach 52, upon the drum 50, when the skip 11 is again raised. To accomplish this, I prefer to provide a second cable reach 59 80 wound on the drum 50 in the reverse direction from that in which the reach 52 is wound. This reach 59 is passed around a cable guide 60 on the base B and around another guide 61 on an arm 62, said arm 85 projecting forwardly from the frame of the machine 10 and being suitably braced to the latter, as indicated at 63. The upper end of the reach 59 is connected to the skip 11. Thus, each time the skip is raised, the cable 59 is unwound from the drum 50, causing rotation of the latter in such a direction as to rewind the cable 52 thereon, the ratchet connection 51 then coming into play to permit the idle retrograde rotation of the drum. Obviously, when the skip 11 lowers, pulls 90 upon the cable 52 and turns the drum 50 in table-turning direction, the cable 59 is rewound upon said drum, in readiness for further performing its function.

I have made novel provision whereby, when the paving machine 10 and the turntable equipment are to be advanced as a single unit, the last upward movement of the skip 11 before such advancement is to be 105 made, is utilized for lifting said turntable equipment free from the ground and placing its weight upon the wheels 17. The mechanism for accomplishing this result is shown in Figs. 6 and 7.

I have previously described the manner in which rotation of the drum 33, in one direction, would effect the desired raising of the turntable equipment, so that it may be moved upon its wheels 17. I will now describe the 115 manner in which this drum 33 is rotated in the desired direction. In the figures just referred to, it will be observed that a gear 64 is secured to the drum 33 and meshes with a pinion 65 which is rotatable and slidable upon the stub shaft 47. Co-acting clutch means 66 are provided on this pinion 65 and the drum 50, so that when said means are engaged, the pinion 65 will be rotated, causing it to rotate the gear 64, thereby driving the drum 33 to attain the desired end.

For elevating the pinion 65 to interengage the clutch means 66, I have operatively connected a suitably mounted lever 67 with said pinion, and have provided an operating cable 120 130

68 for said lever, said cable passing over appropriate guides 69 and extending rearwardly to be controlled by the operator of the machine 10. Thus, whenever the operator is in readiness to advance the machine and the turntable equipment, it is only necessary to actuate the cable 68 in the proper manner when raising the skip 11. Then, the cable 59 rotates the drum 50 and the latter, by means of the inter-engaging clutch means 66, drives the pinion 65. This pinion in turn drives the gear 64 and the drum 33 is thus rotated to wind the cables 32. These cables pull upon the cables 31, turning the cranked axles 29 so as to raise the entire turntable assembly clear of the ground and place its weight upon the wheels 17. Then, as the turntable assembly is connected with the machine 10 for advancement with the latter, the entire assemblage may be forwardly moved to the desired extent.

The preferred manner of connecting the turntable equipment with the machine 10, is shown most clearly in Figs. 1, 3 and 9. From these views, it will be seen that a horizontally positioned, U-shaped frame 70 is interposed between the machine 10 and the base B. The arms of this frame 70 are pivoted on transverse axes 71 to the rear end of the base B, and the arm-connecting, rear portion of said frame 70 is connected with the front end of the machine 10, preferably with its front axle 72. In establishing this connection, I prefer to provide a transverse horizontal rod 74 spaced in front of the axle 72 and having rearwardly turned ends 75 which are suitably secured to said axle. A slide 76 is provided with rollers 77 movable along the rod 74 and by any desired means such as a bolt 78, said slide is connected to the aforesaid arm-connecting portion of the frame 70.

The connections employed at the front and rear ends of the frame 70, not only permit the necessary vertical movement of the turntable assembly for purposes above set forth, but the slide 76, rod 74 and associated parts, permit slight relative movement of the machine 10 with respect to the frame 70, which is essential, as it is practically impossible to advance the cumbersome paving machine exactly down the center of the grade.

While excellent results may be obtained from the general construction herein shown and described, it is to be understood that the present disclosure is principally for illustrative purposes, and that within the scope of the invention as claimed, numerous variations may be made.

60 What is claimed is:—

1. In combination with a cement mixing machine; a truck turntable adjacent said machine upon which to forwardly drive a loaded truck, and means operatively connecting said turntable with a movable portion of

said machine for utilizing the movement of said portion to reverse the position of the turntable, permitting dumping of the truck at the most advantageous position and allowing forward driving of said truck from the 70 turntable.

2. In combination with a cement mixing machine having a skip movable from a lowered receiving position to a raised discharge position; a truck turntable adjacent the 75 skip when the latter is lowered and positioned to receive a forwardly driven truck, and means for automatically turning said turntable one-half revolution when said skip lowers, thereby reversing the truck to 80 dump into the skip and permitting forward driving of said truck from the turntable.

3. In combination with a cement mixing machine having a skip movable from a lowered receiving position to a raised discharge position; a truck turntable adjacent the 85 skip when the latter is lowered and positioned to receive a forwardly driven truck, and means for automatically turning said turntable one-half revolution when said 90 skip lowers, thereby reversing the truck to dump into the skip and permitting forward driving of said truck from the turntable, said means including provision for permitting the turntable to remain stationary while 95 the skip ascends.

4. In combination with a cement mixing machine having a skip movable from a lowered receiving position to a raised discharge position; a truck turntable adjacent 100 the skip when the latter is lowered and positioned to receive a forwardly driven truck, and means connected with said skip for utilizing the weight of the latter to turn said turntable one-half revolution when said skip 105 lowers, thereby reversing the truck to dump into the skip and permitting forward driving of said truck from the turntable.

5. In combination with a cement mixing machine having a skip movable from a 110 lowered receiving position to a raised discharge position; a truck turntable adjacent the skip when the latter is lowered and positioned to receive a forwardly driven truck, gearing for turning said turntable, a drum 115 having a one-way driving connection with said gearing for driving the latter in table-turning direction, a cable wound on said drum and connected with said skip for turning the drum in table-turning direction 120 when the skip descends, guiding means for said cable, and means for retrogradely rotating said drum as the skip is raised, thereby rewinding said cable.

6. In combination with a cement mixing 125 machine having a skip movable from a lowered receiving position to a raised discharge position; a truck turntable adjacent the skip when the latter is lowered and positioned to receive a forwardly driven truck, 130

- gearing for turning said turntable, a drum having a one-way driving connection with said gearing for driving the latter in table-turning direction, a cable wound on said drum and connected with said skip for turning the drum in table-turning direction when the skip descends, guiding means for said cable, a second cable wound reversely on the drum and connected with said skip for retrogradely rotating said drum to rewind the first named cable as the skip ascends, and guiding means for said second cable.
7. In combination with a cement mixing machine; a truck turntable adjacent the same and having a base which normally rests on the ground, normally idle wheels for said turntable, and means connected with a movable portion of said machine for utilizing the movement of said portion to raise the turntable free of the ground and place its weight upon said wheels when the table is to be moved from one place to another.
8. In combination with a mobile paving machine having a skip at its front end movable from a lowered receiving position to a raised discharge position; a mobile truck turntable in advance of and connected with said paving machine for progress therewith, said turntable being positioned to permit forward driving of a loaded truck onto the same, and means for automatically turning said turntable one-half revolution from its truck-receiving position when the skip is lowered, thereby reversing the truck for dumping into said skip and permitting forward driving of the truck from said turntable,
9. In combination with a mobile paving machine having a skip at its front end movable from a lowered receiving position to a raised discharge position; a mobile truck turntable in advance of and connected with said paving machine for progress therewith, said turntable being positioned to permit forward driving of a loaded truck onto the same, and means for automatically turning said turntable one-half revolution from its truck-receiving position when the skip is lowered, thereby reversing the truck for dumping into said skip and permitting forward driving of the truck from said turntable, said means including a one-way connection permitting raising of the skip without turning the turntable.
10. In combination with a mobile paving machine having a skip at its front end into which to dump paving material from a truck, said skip being movable from a lowered receiving position to a raised discharge position; a mobile truck turntable in advance of and connected with the paving machine for progress therewith, and operating connections between said skip and said turntable for utilizing movement of the former to turn the turntable.
11. In combination with a mobile paving machine having a power-raised gravity-lowered skip at its front end; a mobile truck turntable in advance of and connected with said paving machine for progress therewith, and operating connections between a part of said paving machine and said turntable for utilizing the weight of said skip to turn the turntable as said skip lowers.
12. In combination with a mobile paving machine having a power-raised gravity-lowered skip at its front end; a mobile truck turntable in advance of and connected with said paving machine for progress therewith, and operating connections between said skip and said turntable for utilizing the weight of said skip to turn the turntable as said skip lowers.
13. In combination with a mobile paving machine having a skip at its front end movable from a lowered receiving position to a raised discharge position; a mobile turntable having a base in advance of and connected with said paving machine for progress therewith, co-acting gearing mounted on the base and the rotatable portion of the turntable for turning the latter, a drum mounted on said base, a ratchet connection between said drum and said gearing for driving the latter when the drum is turned in one direction and for permitting idle retrograde turning of said drum, a cable wound on said drum and operatively connected with a part of the paving machine for driving the drum in table-turning direction when the skip lowers, guiding means for said cable, and means for retrogradely turning said drum as the skip is raised, thereby rewinding said cable.
14. In combination with a mobile paving machine having a skip at its front end movable from a lowered receiving position to a raised discharge position; a mobile turntable having a base in advance of and connected with said paving machine for progress therewith, co-acting gearing mounted on the base and the rotatable portion of the turntable for turning the latter, a drum mounted on said base, a ratchet connection between said drum and said gearing for driving the latter when the drum is turned in one direction and for permitting idle retrograde turning of said drum, a cable wound on said drum and operatively connected with said skip for driving the drum in table-turning direction when the skip lowers, guiding means for said cable, and means for retrogradely turning said drum as the skip is raised, thereby rewinding said cable.
15. In combination with a mobile paving machine having a skip at its front end movable from a lowered receiving position to a raised discharge position; a mobile turntable having a base in advance of and connected with said paving machine for progress therewith, co-acting gearing mounted on the

- base and the rotatable portion of the turn-table for turning the latter, a drum mounted on said base, a ratchet connection between said drum and said gearing for driving the latter when the drum is turned in one direction and for permitting idle retrograde turning of said drum, a cable wound on said drum and operatively connected with said skip for driving the drum in table-turning direction when the skip lowers, a second cable wound reversely on the drum and operatively connected with said skip for retrogradely turning the drum to rewind the first named cable as the skip is raised, and guiding means for said cables. 15 70 75 80
16. In combination with a mobile paving machine adapted to be intermittently advanced along a grade and having a receiver at its front end in which to dump paving material from a truck; a truck turntable in advance of said paving machine and normally resting upon the grade, normally idle wheels for said turntable, connecting means between said paving machine and said turntable for advancing the latter with the former, and means driven by a part of said paving machine for raising the turntable from the grade and placing its weight upon said wheels when the paving machine and turntable are to be advanced. 20 25 30 35 40 45 50 55 60 65 70 75 80 85 90 95 100 105 110 115 120 125
17. In combination with a mobile paving machine adapted to be intermittently advanced along a grade, said machine having a skip at its front end movable from a lowered receiving position to a raised discharge position; a truck turntable in advance of said paving machine and normally resting upon the grade, normally idle wheels for said turntable, connecting means between said turntable and said paving machine for advancing the former when the latter is advanced, and manually controlled means actuated by a part of the paving machine for raising the turntable from the grade and placing its weight upon said wheels upon the last ascent of the skip prior to advancing the machine. 5 10 15 20 25 30 35 40 45 50 55 60 65 70 75 80 85 90 95 100 105 110 115 120 125
18. In combination with a mobile paving machine adapted to be intermittently advanced along a grade, said machine having a skip at its front end movable from a lowered receiving position to a raised discharged position; a truck turntable in advance of said paving machine and normally resting upon the grade, normally idle wheels for said turntable, connecting means between said turntable and said paving machine for advancing the former when the latter is advanced, and normally inactive manually controlled means actuated by said skip for raising the turntable and placing its weight upon said wheels upon the last ascent of the skip prior to advancing the machine. 5 10 15 20 25 30 35 40 45 50 55 60 65 70 75 80 85 90 95 100 105 110 115 120 125
19. In combination with a mobile paving machine; a truck turntable in advance there-

In testimony whereof I have hereunto affixed my signature.

BENJAMIN H. FLYNN.
